BAG LOCK

Filed Dec. 18, 1925

INVENTOR.
William C. Hering.
BY Fred C. Fischer:
ATTORNEY

UNITED STATES PATENT OFFICE.

WILLIAM C. HIERING, OF NEWARK, NEW JERSEY, ASSIGNOR TO J. E. MEROOTT CO., OF NEWARK, NEW JERSEY, A CORPORATION OF DELAWARE.

BAG LOCK.

Application filed December 18, 1925. Serial No. 76,150.

This invention relates to fastening devices, more particularly as applied to bags, using the term generically, to hold two adjacent parts firmly together along their meeting 5 edges.

One of the objects of the invention is to provide a hasp, hingedly engaged on one of the members of the article to be secured, and carrying a spring actuated detent engageable 10 with a keeper fixed on the mating member of the article.

A further feature is in the provision of means by which the detent may be normally retracted and other, key actuated means, co- 15 operative therewith, to prevent retraction of the detent by the first named means, but which permits of engagement irrespective of the key actuated means.

Another aim is to produce means where- 20 by the hasp is normally raised out of engage- ment with the keeper.

It is a further purpose to provide a device composed of few and simple parts, capable of economic production, readily assembled to 25 produce a neat and attractive fastener susceptible of wide general application.

These and other important aims, objects and purposes are accomplished by the novel construction, combination and arrangement 30 of parts hereinafter described and shown in the accompanying drawing, constituting an essential portion of this disclosure, and in which:—

Figure 1 is a front elevational view of an 35 embodiment of the invention, illustrating its application.

Figure 2 is a side view of the same, shown in a closed position.

Figure 3 is a similar view but showing the 40 hasp as raised and released from the detent.

Figure 4 is a longitudinal sectional view taken on line 4—4 of Fig. 1 and drawn to an enlarged scale.

Figure 5 is an enlarged plan view of the 45 lock casing and mechanism therein, looking from the under side thereof, the parts being in an unlocked position.

Figure 6 is a similar view of the same, as the parts appear in a locked position.

Figure 7 is a bottom plan view of the 50 hinge, carrying member and hasp raising spring.

Figure 8 is a detail perspective view of the lock parts in their relative position.

Figure 9 is a perspective view of one type 55 of keeper.

Referring in greater detail to the drawing, the numeral 10 designates one of the members of the bag or other article and 11 the mating member of the same. 60

The permanent, hinge carrying element 12 of the lock consists of a metal plate shaped to produce a hollow casing raised slightly above the surface of the bag member 10 by reason of its enclosing walls 13, from which project prongs 14, adapted to pass through the wall 10 and also a thin flat metal re-enforcing plate 15, if the material is of a yielding pliable nature, the prongs being bent tightly thereover to afford a secure grip. 70

The shape of the casing may be varied at will and the manner of securing it to the wall 10 is one of choice, not necessarily exactly as shown.

The front portion of the casing, disposed 75 parallel and adjacent the edge of the wall 10, is sheared at the ends and curled to form an elongated central hinge element 16, open partially at its lower side to admit the free end 17 of a flat spring, the main portion 18 of 80 which is disposed within the casing 12 and held firmly against the inner surface of its top wall by prongs 19 sheared from the rear wall, in a manner like the prongs 14, and bent to impinge on the rear marginal edge 85 of the spring, as best seen in Figs. 4 and 7.

A hasp 20 is formed of sheet metal with down turned edges 21, similar to the edges 13 of the hinge casing and of the same height, these edges reenforcing the hasp and improv- 90 ing its appearance.

The main portion of the hasp is of uniform width, blending into a wider base portion, sheared at the middle and curled on each side to present two hinge elements 22, 95 conforming with the element 16 and engaged thereto by a hinge pin 23 in the usual manner, and it is to be noted that the spring end 17 is arranged to operatively engage the central portion of the hasp, in front of the axis 100 of the hinge, acting to press the hasp outward or away from the bag material 11, over which it extends.

The forward, free, end of the hasp 20

contains a circular opening 24, the surrounding metal being drawn upward to form a short cone or cylinder 25, cut out on the side adjacent the hinge, as at 26, for a purpose 5 which will presently appear.

Enterable into the cone 25 is the rounded circular head 27 of a keeper stud, the reduced stem 28 of which extends from a disc 29, loosely fitting the opening 24 and formed 10 on a plate 30 held to the bag member 11 by prongs 31 passing therethrough and clinched over a thin reenforcing plate 32 on the under side of the material.

The lock mechanism is contained in an 15 oblong rectangular casing 33 of lesser width than the lever 20 and secured centrally on its free end by prongs 34, extending from the side walls 35 of the casing, which join the front and rear end walls 36 and 37 respectively, to constitute a complete closure 20 except for a key hole 38 in its cover portion.

Slidably mounted in the lock casing 33, against the inner surface of its cover, and filling the space between its side walls 35, 25 is a push piece 39 having a narrowed front end 40 extending through an opening in the front wall 36, this projection being smoothly finished to be operated by the fingers in releasing the catch, as will be seen.

30 The projection 40 has at its sides square shoulders 41 that limit the outward movement, of the push piece 39, which contains a central elongated opening 42 into which the tube 25 enters and also the head 27 of 35 the detent.

A recess 43 in the inner portion of the push piece separates the same into two forks 44, 45, both forks being reduced at their left hand side edges to provide extensions 46, 47.

40 Disposed on the push piece are the downwardly flanged edges 48 of a flat bolt 49 having forwardly extending arms 50, spaced substantially in accordance with the width of the opening 42, and into this space 45 extends a central forwardly projecting lug 51, concavely curved at the front edge and rounded on its upper corner to make contact with the detent head 27, below which it engages, when passed through the opening 50 26 in the tube 25.

55 A pad 52 is bent at a right angle from the rear edge, at the center of the bolt 49, to contact with the casing cover 33, being movable in the recess 43 of the push piece 39, and extending rearwardly from the pad is a lug 53, adapted to retain the notched end 54 of a bent flat spring 55 in operative position on the pad.

60 The opposite end of the semi-elliptical spring 55 bears against the inner surface of a channel shaped controller 56, movable transversely in the rear portion of the casing, against the wall 37 and is provided with two indentations 57, 58, either of which is 65 engageable with a protuberance 59 on the

inner surface of the wall to hold the controller in either of its adjusted positions as moved by a key 60 inserted through the key hole 38.

The lower wall of the controller 56 is shaped to present two forwardly extending stops 61, 62, relatively wide and narrow, and so arranged that when the controller is moved to one side of the casing as to permit the push piece 39 to be pressed inwardly, as shown in Fig. 5, but when at the opposite side of the casing the fork projections 46, 47 make contact with the stops 62, 61 preventing retraction of the push piece 39 but permitting the bolt 49 to move inwardly against the pressure of the spring 55.

The upper wall of the controller 56 presents similar but longer forwardly extending arms 63, 64 having between them a space through which the ward of the key 60 may extend when entered, the ward being contactable with either arm of the controller by which it is moved by turning the key thereby permitting the push piece to be pressed in or held positively extended as in Fig. 6.

It is to be noted that the bolt 49 is at all times free to recede, as by making forcible contact with the detent head in closing the hasp irrespective of the position of the controller, or by pressing the push piece 39 into the lock when the controller is in position to allow this to be done, as in Fig. 6.

Thus it is possible, by proper use of the key to prevent entrance to the bag at will or to release it for actuation by the push piece, in which case the hasp is instantly raised by the spring 18 and retained until the hasp is pressed down and catch element 51 reengages with the detent.

From the foregoing it will be seen that a simple device for this purpose has been disclosed in the preferred form of its embodiment, but it is not desired to restrict the details to the exact construction shown, it being obvious that changes, not involving the exercise of invention, may be made without conflicting with the scope of the appended claims.

Having thus described my invention, what I claim as new and desire to secure by Letters Patent, is:—

1. A bag lock comprising a support fixed to one portion of the bag, a detent on the other portion, said detent having a rounded raised head and an attenuated shank, a hasp hinged to said support and having an opening to receive said detent, a casing on said hasp, a slide bolt movable in said casing to engage below the head of said detent, a push piece independently movable in said casing and adapted to retract said bolt, and a spring operatively engaging the bolt.

2. A lock for separable members comprising a hasp pivoted on one member, a spring

to normally raise the hasp, a detent fixed on the other member, a lock casing carried by said hasp, a spring actuated bolt engageable with said detent, a push-piece also actuated by the bolt spring and movable independently of said detent to cause disengagement of the bolt with the detent, and means carried by said hasp to receive said detent whereby the hasp is held in register therewith.

3. A lock for separable members comprising a hasp pivoted on one member, a spring to normally raise the hasp, a detent fixed on the other member, a lock casing carried by said hasp, a spring actuated bolt engageable with said detent, a push-piece also actuated by the bolt spring and movable independently of said detent to cause disengagement of the bolt with the detent, and a key actuated controller slidable transversely in said casing, said controller permitting or preventing motion of said push piece.

4. A lock for separable members comprising a hasp pivoted on one member, a detent on the other member, a lock casing carried on said hasp, a bolt in said lock casing adapted to engage said detent, an extending push piece manually operable to retract said bolt, a controller slidable transversely in the lock casing, said controller having key con-

tacting arms in one plane and stops in another plane, said stops arresting movement of said push piece when in one position and permitting movement when in another position, and a spring common to both the bolt and controller.

5. A lock for separable members comprising a hasp pivoted on one member, a detent on the other member, a lock casing carried on said hasp, a bolt in said lock casing adapted to engage said detent, an extending push piece manually operable to retract said bolt, a channel shaped controller slidable in said lock casing against the rear wall thereof, arms on said controller adapted for key actuation, stops on the controller adapted to be moved into or out of position to intercept movement of said push piece, means cooperative between the controller and rear wall of the lock casing to retain the controller in either of its adjusted positions, and a single flat spring pressing said controller against the position retaining means at one end, the other end of the spring impinging on said pushpiece and contracting with said bolt whereby either is able to move independently.

This specification signed and witnessed this 17th day of December, 1925.

WILLIAM C. HIERING.
